RESPIRATOR MASK

Vernon F. Gongoll, Shillington, Guy G. Klinger, Wernersville, and David G. Ullrich, West Reading, Pa., assignors to The Electric Battery Storage Company, Philadelphia, Pa.

Filed Dec. 31, 1958, Ser. No. 53,992

Term of patent 14 years

(Cl. D83—1)

Fig. 1.

Fig. 2.

Fig. 3.

FIG. 1 is a front elevational view of a respirator mask showing our new design;

FIG. 2 is a side perspective view thereof, the opposite side being substantially the same; and

FIG. 3 is a rear view thereof.

We claim:

The ornamental design for a respirator mask, substantially as shown and described.
